UNITED STATES PATENT OFFICE.

HENRY D. STOVER, OF NEW YORK, N. Y., AND WILLIAM W. W. WOOD, OF PHILADELPHIA, PENNSYLVANIA; SAID WOOD ASSIGNOR TO SAID STOVER.

IMPROVED SHUTTERS FOR THE PORT-HOLES OF VESSELS, &c.

Specification forming part of Letters Patent No. 35,129, dated April 29, 1862.

To all whom it may concern:

Be it known that we, HENRY D. STOVER, of New York, in the county and State of New York, and WILLIAM W. W. WOOD, of Philadelphia, in the county of Philadelphia and State of Pennsylvania, have invented certain new and useful Improvements in the Construction of War-Vessels, Floating Batteries, and Sea-Coast and other Fortifications; and we hereby declare the following to be a full, clear, and exact description of the same, reference being had to the accompanying drawings, in which the several figures represent views in elevation, plan, and section of our improvements.

Late improvements in the building of warships, floating batteries, &c., have rendered such structures almost, if not entirely, impregnable. Said improvements, however, were confined mainly to the construction of the armor, and had for their principal object impenetrability, economy of cost and weight, durability, and convenience of construction. Although war-vessels and batteries thus constructed offer to the gunners and occupants comparatively perfect protection, yet from the fact that the missiles and projectiles are in proportion the more formidable it is evident that if by chance or skill or otherwise one such projectile were thrown in among the gunners the execution resulting from it would be of the most fearful character. It is therefore important so to construct war-vessels or batteries that there shall be little or no opening, gap, hole, or embrasure through which balls, bolts, or other kind of projectile may be fired or thrown into the interior of the ship; but vessels as heretofore constructed are necessarily provided with embrasures or openings called, "port-holes," through which the guns are thrust while being sighted or aimed and fired. These port-holes are exceedingly dangerous, inasmuch as they offer an opening large enough to ship projectiles of the largest caliber, and, moreover, serve as an easy target to the gunners of the enemy. On the other hand, the attendants to the guns are placed in immediate vicinity or about the port-hole, from which it will be evident that a single shot penetrating the ship through the port-hole must necessarily cause execu-

tion, besides endangering the ship by explosion, &c.

The object of our invention, therefore, is to so construct, combine, and arrange shields or armors to port-holes as to effectively protect the gunners and interior of the ship, without, however, interfering with the working of the guns; and our invention consists, first, in the construction and arrangement of shields or armor to the port-holes of war-vessels, floating batteries, &c., substantially as hereinafter shown and described, by forming them of two or more plane or curved plates impenetrable to shot and arranged at such angles in relation to each other and to the side walls of the said vessel or batteries as to insure the glancing off of the projectiles thrown upon or against them; second, in the combination, with movable shields or plates hinged or otherwise suspended to the side of the ship, so that the same may be opened or closed, of convex-shaped or angular blocks arranged to close the top opening between the shields and side walls and to hold the said shields, when closed, at the requisite angle in relation to each other and to the side walls of the ship, &c.; third, in the combination of movable shields, constructed and arranged as hereinafter described, with levers, chains, springs, or other mechanism, whereby the said shields may be worked at pleasure by hand from the inside of the ship or battery; fourth, the combination, with movable shields of the method hereinabove described, of hanging the same or of the employment of some other mechanism whereby the shields are actuated automatically to close either against each other or against the gun; fifth, in forming corresponding outer recesses to the inner or closing edges of the shields of such shape as that the said shields by closing against the gun shall leave a vertical space sufficiently narrow to prevent projectiles from penetrating, yet wide enough to allow of the guns being sighted through it; sixth, in the method of hanging the shields made of spherical or plane surfaces at such angles in relation to each other as that while closing automatically, as described, they shall constitute both the roof and shield to the port-hole.

To enable others skilled in the art to carry

into effect this, our invention, we shall now proceed to describe the construction, arrangement, and combination of our improved shields or armors to port-holes and the manner of operating them.

In the accompanying drawings, Figures 1, 2, 3, and 4 represent, respectively, front, side, sectional, and plan views of a shield or armor applied in illustration to the sloping or inclined side walls of a ship.

A in the said figures are the side walls, which are perforated at suitable intervals for the guns. On either side of the port-hole or embrasure is a quadrangular shield, B, with an outer flat, convex, or concave surface, the two converging to constitute angles relatively to each other and in relation to the side walls of the vessel as will insure the glancing off of the balls or other projectiles that may be fired or thrown upon or against them. In these figures the shields form when in a normal position an angle of forty degrees (more or less) with the side walls, and consequently an angle of one hundred degrees (more or less) with each other.

The shields are hung in suitable sockets fast in and to the ship-walls, and are capable of being moved upon their hinge-lines *a b* and *c d*. The shields thus act like doors or shutters to the port-holes, and are or may be operated from within the ship by means of levers or bars, which may be permanently fixed or attached to the shields. If it be desirable that the shields close and remain closed against the guns while the latter are being worked, they may be made to close automatically. We have here shown the shield-operating lever *c* combined with weights *D*, suspended to the ends of the lever by means of a cord passing through a loop, *e*, or over a pulley on the interior of the side wall. The weight, having a tendency to draw the lever ends toward the side walls, will necessarily cause the shields to converge or to close against the gun-barrel.

Instead of weights, chains, or springs, any other suitable mechanical device may be used to effect the same end. The shields are centrally, or thereabout, recessed, to allow of the gun to be thrust out and worked in a manner as if there were no shields. The muzzle of the gun is passed through the opening formed by the recesses in the shields, which are of such shape as to snugly fit or clasp the gun-barrel, or at least approach it sufficiently near to afford no room for balls or projectiles to penetrate the interior of the ship. The recessed parts, it will be seen, are not completely circular, and the opening formed by them is (the shields being closed) of a transverse diameter smaller than the outside diameter of the gun-barrel. By thus shaping the recess the gun when placed in position to be fired will form between the two shields a gap, through which the gunners may conveniently and under perfect protection make the neces-

sary observations, aim, and sight, and otherwise work the gun. Upon the gun being withdrawn from the port-hole, the shields may be closed by hand; or they may close automatically by the arrangement of weights, springs, &c., before described and referred to.

The opening on the top and bottom between the shields and side walls may be closed by means of semi-spherical or semi-pyramidal blocks or roofs secured to the sides of the ship or boat, as shown in the drawings; or they may be made simply to support the shields when closed or placed in their normal positions at the requisite angle in relation to the side walls of the ship. In the former case the blocks are provided with stays *m*, which fix the position of the shields.

Figs. 5, 6, and 7 show both in the general arrangement and combination and in the details substantially the same mode of construction of shields to port-holes. In these figures the said shields are shown applied to straight or perpendicular side walls, and are operated automatically by means of a powerful spring in lieu of weights.

Figs. 8 and 9 represent a modification or simplification of my improved shields, embracing, however, all the features of my invention. *G*, in the said figures, are shields of triangular or trapezoidal form, hinged upon the inclined sides *o p* and *o p'*, so that the gravity of each shield shall cause it to close upon and against the supporting-bracket *H*, whose form is such as to leave a vertical sighting-gap for the gunners to sight through. These shields, while presenting surfaces, whether plane or curved at right angles in relation to the side walls of the vessels as will reflect any projectile fixed against them, constitute at the same time the roof to the port-hole.

Having thus described the nature of our invention and in what manner the same is or may be performed, we declare that we do not claim the application to port-holes of shutters to keep the weather out; nor do we claim, broadly, the use of plates, shields, or armors for the protection of the interior of war-vessels, floating batteries, and sea-coast and other fortifications; but

We do claim—

1. The construction and arrangement of shields or armor to the port-holes of war-vessels or floating batteries, substantially as herein shown and described, by forming two or more plane or curved plates impenetrable to shot and arranged at such angles in relation to each other and to the side walls of the said vessel or battery as to insure the glancing off of the projectiles thrown upon or against them, as set forth.

2. In combination with movable shields, operating as described, the convex shaped or angular blocks arranged to close the top opening between the shields and side walls, and to hold the said shields when closed at their

requisite angles, substantially as shown and described.

3. In combination with such movable shields closing automatically or otherwise, in the manner described, so forming corresponding recesses to the inner edges of the shields as that the shields by closing against the gun shall leave a vertical space sufficiently narrow to prevent projectiles from penetrating, yet wide enough to allow of the gun being sighted through it.

In testimony whereof we have signed our names to this specification before two subscribing witnesses.
